HAIRPIN

Mirabeau C. Towns, Jr., Sparta, N. J.

Application May 5, 1949, Serial No. 2,447

Term of patent 14 years

(Cl. D86—10)

To all whom it may concern:

Be it known that I, Mirabeau C. Towns, Jr., a citizen of the United States, residing at Sparta, State of New Jersey, have invented a new, original, and ornamental Design for a Hair Pin, of which the following is a specification, reference being had to the accompanying drawing, forming a part thereof.

In the drawing, Figure 1 is a perspective view of the hair pin, showing my new design; Figure 2 is a side elevation thereof; Figure 3 is a top plan view thereof; Figure 4 is a bottom plan view thereof; and Figure 5 is an end elevation thereof.

I claim:

The ornamental design for a hair pin, as shown.

MIRABEAU C. TOWNS, JR.
